FREDERICK C. OVERBURY, OF HILLSDALE, NEW JERSEY, ASSIGNOR, BY MESNE ASSIGNMENTS, TO THE PATENT AND LICENSING CORPORATION, OF BOSTON, MASSACHUSETTS, A CORPORATION OF MASSACHUSETTS

METHOD OF AND APPARATUS FOR MAKING STRIP SHINGLES

Application filed August 16, 1926. Serial No. 129,484.

This invention relates to a method of and apparatus for making fabricated roofing elements, more particularly the type of element commonly known as a strip shingle. Roofing elements of this general class are customarily made with a fibrous base or foundation of sheet material composed of rag or asbestos fibers or the like, which has been formed on a paper-making machine. The fibrous foundation is saturated with a suitable waterproofing material such as low melting-point asphalt after which it is coated on one or both faces with a waterproofing layer of high melting-point or blown asphalt which by reason of its relatively high melting point and tough and rubbery consistency is particularly suited for this purpose. The waterproof coating layer is thereupon surfaced with a protective masking layer of comminuted or granular material in order to protect the asphalt layer from the deteriorating action of the weather, particularly the sun's rays. The granular material which may consist of crushed slate, brick, tile, ground cork, sawdust, or other equivalent material, may be applied to both surfaces or to the weather side only of the strip shingle. In the latter case, if there be a coating on the under side, such coating is usually dusted with talc, powdered mica or equivalent material, to make the surface non-sticky. From a sheet thus prepared, strip shingles of suitable size and shape are cut and such strip shingles have been sold as a finished product ready for use. It has been found advantageous, however, to protect the cut edges of such roofing elements which are exposed to the weather, since such edges, if not protected, make it possible for atmospheric moisture to soak into or dry out of the fibrous base of the shingle through the cut ends of the fibers which appear at such edges. These changes of moisture content, together with loss of volatile constituents of the saturant, tend to cause the shingle to "sponge" or "bulk" and the corners to warp and curl, causing rapid deterioration of the roofing elements. The life of the shingle may be greatly prolonged therefore by sealing the cut edges which are to be exposed to the weather with suitable coating

material, this material being preferably surfaced with grit or the like to protect it from the light.

I am aware that broadly speaking it is not new to make strip shingles with exposed edges sealed, but I have devised a novel method for producing such an article, and apparatus for carrying out the steps in the method. This will be more clearly understood from the disclosure on the drawing, of which:—

Figure 1 represents conventionally apparatus for operating on a sheet of raw felt to convert it into the finished product.

Figures 2 and 3 are sections on the lines 2—2 and 3—3 respectively of Figure 1.

Figure 4 is a fragmentary plan of a portion of the sheet of felt indicating one of the several possible arrangements of slots and lines of cut on the sheet to form the individual roofing elements.

Figure 5 shows a modified form of a portion of the apparatus.

Referring to the drawing in detail, a roll of raw roofing felt is indicated at 10. The sheet from the roll is led through a pair of rolls 11 which are constructed to cut out longitudinal series of transversely extending slots as indicated in Figure 4, or to make any other cut-outs desired according to the shape of the strip shingle to be formed. The sheet is then passed through a container 12 in which is maintained a suitable pool of impregnating material 13 such as low melting-point asphalt or its equivalent. The slotting and saturating steps may be interchanged if desired. The excess saturant may be removed from the sheet as it emerges from the container 12 as by a pair of rolls 14 from which the sheet is led to a series of dry and cooling rollers 15. The saturated and partially cooled sheet may then be coated on its weathered side as by a suitable spout or series of spouts 16 which may be used to deposit a supply of water-proofing material such as blown asphalt on the upper surface of the sheet. This coating may be spread as by a roll 17 to form an even layer. If desired, the under surface of the sheet may also be coated, a suitable roll 18 being provided for the purpose to pick up on 100

its periphery molten asphalt directly from a suitable supply 19 thereof or by contact by an intermediate feed roll 20. Suitable means (not shown) are supplied for keeping the saturant in the container 12 and the coating material in the spout 16 and the container 19 at the desired temperatures to maintain in these materials the proper consistencies. The coated sheet is then surfaced with comminuted material on one or both sides. As shown, a hopper 21 is provided to deposit grit of any desired kind on the upper surface of the coated sheet while the coating is still hot and sticky. A suitable container 22 is positioned to catch surplus grit which may fall off the edges or through the slots of the sheet. The sheet may then be passed about a roll 23, the pressure against which serves to force sufficient of the grit into firm engagement with the coating to cover the same completely and to be held partially embedded therein, excess grit passing on over the roll 23 and falling back into the hopper 21. At any suitable point, a dust box 24 may be supplied to dust the under side of the sheet with talc or other non-sticky surfacing material. The sheet is then led over a number of cooling rollers 25, after which it is slit longitudinally as by suitable rolls 26, the lines of slit passing through the slots as indicated at 27 in Figure 4 to form the butt edges of the strip shingles. The slitter 26 may be made to slit also between the rows of slots as at 37, or if preferred this line of slit may be cut subsequently. The slitting rolls 26 are followed at once by a set of edge-coating rolls 28 which are located to dip into a suitable supply of coating material 29. These rolls 28 are each preferably provided with a central flange 30 which forms with the periphery of the roll shoulders 31 adapted to pick up and hold sufficient coating to seal completely the butt edges of the shingle strips which come in contact therewith by locally coating these edges, that is, by confining the application of coating material substantially to the edges so that there is little or no extension of the edge coating onto the front face of the shingle strip. When the lines of slit 27 have been cut in the sheet through the series of slots, shingle-simulating tabs are thus formed which are somewhat limp where asphalt-saturated fibrous material has been used in preparing the roofing sheet, since such material is semi-flexible, especially when warm. In order to support the strips of roofing which have been slit from the sheet, I may provide suitable tables 32 on which the strips may slide, the tabs on the strips formed by the slits 27 being allowed to extend over the edges of the tables 32 to engage the peripheries of the coating rolls 28. The rolls 28 may be arranged as shown in Figure 1 to engage the edges of the strips with the shoulders 31 to

maintain them on a level with the tables 32, or the edges may be allowed to sag somewhat, as in Figure 2, to engage the shoulders 31, or the upper portion of the rolls 28 may be positioned above the table 32 to bend the strip edges upwardly while in contact with the shoulders 31. By thus bending the edge portions adjacent to the slits out of the plane of the supported portions of the strips, the cut edges of the slits are well separated to receive ample and independent coatings of asphalt. After leaving the coating rolls 28, the strips pass a grit hopper 33 which is adapted to deposit a continuous supply of grit on the freshly coated edges of the strips. Suitable troughs 34 are preferably placed beneath the hoppers 33, each trough being shaped with a diminishing depth as shown in Figure 1, so that the tabs of the strips which droop over the edges of the tables 32 are picked up by their butt edges on the deeper end of the trough which is supplied from above with grit from the hopper 33, and travel to the upper end of the trough in contact with a supply of loose grit from the hopper 33, which is swept along the trough by the tabs, the surplus being caught in a suitable receptacle 35. This contact of the coated edges of the strips with the grit in the trough 34, together with the grit showered from the hopper 33, surfaces the edge coating of the strips with grit. Individual elements may then be cut from the strips by a suitable cutter 36 as on the lines 38.

A modified device for coating the edges of the slit strips is indicated in Figure 5. Instead of the edge-coating rolls 28 to apply coating material to the edges after they have been slit by the rollers 26, I may apply a narrow stream of asphalt either to the knife of the slitting roll 26 itself, or to the sheet immediately in front of the knife as shown in Figure 5. This line of fresh hot asphalt may be supplied as by a suitable spout 39, as shown, or by any other suitable means. The slitting roll 26 cutting the sheet immediately after the application of the narrow stream of hot asphalt works in this asphalt and carries some of it into the cut. The cutting blades on the roll 26 are also preferably so shaped that the edges of the cut will be sufficiently separated to allow some of the asphalt to flow around behind the blade into the cut to complete the sealing of the edges.

Having thus described an embodiment of my invention, it should be evident to those skilled in the art that many changes and modifications may be made therein without departing from its spirit or scope as defined by the appended claims.

I claim:

1. A method of making fabricated roofing elements, which comprises cutting a series of transverse slots in a sheet of roofing material of indeterminate length, saturating the sheet

- with waterproofing material, applying coating material to a face of the slotted and saturated sheet, surfacing the coating with comminuted material, slitting the sheet thus coated and surfaced longitudinally into strips through said slots, coating the newly cut edges only of the butt portions of the strips with additional waterproofing material, surfacing the edge coatings with grit, 10 and cutting individual elements from the strips, each cut passing through a slot.
2. A method of making roofing elements, which comprises cutting longitudinal series of transverse slots in a sheet of roofing base 15 of indeterminate length, said slots being spaced from both edges of the sheet, saturating the sheet with waterproofing material, coating a face of the sheet with bituminous compound, surfacing the coating with grit, 20 slitting the sheet longitudinally through said slots, applying additional coating locally to the cut edges resulting from the slitting, and surfacing the edge coating with grit.
3. Steps in the method of making roofing 25 elements, which comprise slitting a sheet of semi-flexible roofing of indeterminate length into longitudinal strips, supporting each strip horizontally for a portion of its width, bending the unsupported portions adjacent to 30 the edges of the slits out of the plane of the supported portions, thus separating the cut-edges of each slit, and applying coating material locally to said cut edges and surfacing the coating with grit while said cut edges are 35 so separated.
4. Apparatus for making strip shingles with sealed butt edges, comprising the following instrumentalities, to wit: means for slotting and saturating a sheet of roofing base, means 40 for coating a face of the saturated sheet with waterproofing material, means for applying grit to the coated face, means for thereafter longitudinally slitting the grit-covered sheet through the slots, means for applying to the 45 newly cut edges only a sealing coat of waterproofing material, means for applying additional grit to the coated edges, and means for cutting individual elements from the strips, each cut passing through a slot.
5. Apparatus for making roofing elements, which comprises means for longitudinally slitting into strips a sheet of semi-flexible roofing material of indeterminate length, means for separating the cut edges of the 55 slits, said separating means comprising a substantially horizontal support for a portion of the width of each said strip arranged to leave the portion of the strip adjacent to a cut edge unsupported, and means for applying liquefied coating locally to the cut edges.
6. Apparatus for making roofing elements, which comprises means for slitting into longitudinal strips a sheet of semi-flexible roofing material, substantially horizontal support 60 means for said strips, said supporting means being arranged to carry said strips for a portion of their width but to leave the portion adjacent a slit edge unsupported, means for applying liquefied coating material to the cut edges of each slit, said coating means comprising a wheel having on its periphery intermediate the ends a radial flange forming with said periphery a pair of shoulders adapted to receive the cut edges of the slit, and a container for coating material into which said wheel is adapted to dip.
7. Apparatus for surfacing a coated edge of a continuous semi-flexible sheet, which comprises a table, means for sliding the sheet longitudinally on the table with a portion of the sheet adjacent to said coated edge projecting over the edge of the table, and means for maintaining a quantity of loose dry surfacing material in contact with the projecting edge of the passing sheet.
- In testimony whereof I have affixed my signature.
- FREDERICK C. OVERBURY.
